UNITED STATES PATENT OFFICE.

PATRICK W. SHIELDS, OF PITTSBURGH, AND LOUIS DE MARKUS, OF MONTROSE, PENNSYLVANIA, ASSIGNORS TO MCKENNA BRASS AND MANUFACTURING COMPANY, INC., OF PITTSBURGH, PENNSYLVANIA, A CORPORATION OF PENNSYLVANIA.

METHOD AND APPARATUS FOR LOW-PRESSURE CARBONATION AND BOTTLING.

Application filed September 29, 1922. Serial No. 591,289.

The present invention relates broadly to bottling soft drinks which require a comparatively low carbonation, and to a method of effecting the desired carbonation.

- 5 In the soft drink industry it is common practice to carbonate or charge ordinary water with from 2 to 8 times its own volume of carbon dioxide, the degree of carbonation depending upon the product desired.
- 10 In ordinary carbonators there is usually provided an excess of carbon dioxide to insure carbonation up to the saturation point of the water at carbonator temperature and pressure. As with certain drinks, such for example as imitation grape drinks, it is desirable to provide only sufficient carbon dioxide to impart the desired palatable characteristics to the drink, it will be apparent that a carbonator which effects carbonation
- 15 up to substantially the saturation point would not be suitable for directly supplying its water to a bottling machine bottling drinks of this character.

By the present invention there is provided improved means for supplying carbonated water of the proper characteristics to bottling machines, it being understood that the term "bottling" as used herein is definitive both of bottle filling and bottle filling and capping machines.

In the accompanying drawings, there are shown for purposes of illustration only certain embodiments of the present invention, these drawings being largely diagrammatic and representing apparatus which may be of any desired construction and in which changes may be made in the construction and operation without departing from the spirit or scope of our broader claims.

40 In the drawings,—

Figure 1 is a chart in rectangular coordinates showing the relation between temperature, pressure, and saturation point of carbon dioxide in water;

45 Figure 2 is a diagrammatic view illustrating one embodiment of this invention; and

Figure 3 is a diagrammatic view, corresponding to Figure 2, illustrating a slightly modified embodiment of the invention.

50 Experience in the use of bottling machines requiring carbonated water has demonstrated the advisability of supplying such water

at comparatively definite pressures. While these pressures obviously vary with different machines, in accordance with the particular design of the machine, each machine is best adapted to operate only over a comparatively definite pressure range. By the present invention it is possible not only to effect the desired degree of carbonation of the water, but to supply the carbonated water at a pressure required by the bottling machine.

Referring first to the chart of Figure 1, the horizontally extending dotted line represents the pressure at which the bottling machine, not shown in the drawings, is best adapted to operate. It will be apparent that a carbonator for supplying such bottling machine may either carbonate at the pressure of the bottling machine, or at any other desired pressure. This will be more fully pointed out hereinafter. In this figure, the lowest and highest temperatures at which tap water is found during the year, are represented respectively by the reference characters t' and t^2 . During the cold months, the water temperature will approach t' as a limit, while during the hotter months it will approach t^2 . An average temperature condition of the tap water may be arbitrarily represented by t . The intersection of a line drawn from t with the dotted line representing the bottling machine pressure, will show that under these conditions the saturation point of the water is at about $4\frac{1}{3}$ volumes. It has already been pointed out that a carbonator which is commercially efficient will produce a substantially saturated solution at its operating temperature and pressure. The temperature will obviously be determined under ordinary conditions by the temperature of the tap water, while the pressure may be determined in any desired manner.

As this degree of carbonation, namely substantial saturation, is not suitable for use in bottling certain soft drinks requiring extremely low carbonation, such as referred to, it is necessary to provide means for effecting an under-saturation. It is extremely difficult, if not impossible, to effect uniform carbonation at under-saturation in ordinary carbonators with known apparatus. This is

due to the difficulty in maintaining the desired proportions of water and carbon dioxide. By the present invention the carbonator is preferably operated at a pressure which is below bottling machine pressure, whereby substantial saturation is effected at this pressure, and then the substantially saturated water is treated to make it capable of absorbing additional carbon dioxide. This may be accomplished by increasing the pressure on the substantially saturated solution whereby an under-saturated solution, at the increased pressure, is provided.

The present application constitutes a continuation in part of our co-pending application Serial No. 591,288, filed September 29, 1922.

Referring more particularly to Figure 2 of the drawings, there is illustrated diagrammatically a carbonator 2 which is adapted to carbonate substantially to saturation at the carbonator temperature and pressure. This carbonator may be provided with a suitable connection 3 for supplying the carbon dioxide gas thereto, and with another connection 4 for supplying the water to be carbonated. The carbonated water, leaving the carbonator at substantially the saturation point, passes through a connection 5 to the inlet of a suitable booster pump 6, which may be operated in any desired manner and may be of any well known construction, for increasing the pressure on the water. The outlet 7 of the pump communicates through a suitable connection 8 with a storage reservoir 9 which in turn has an outlet connection 10 leading to the bottling machine (not shown).

As the pressure on the water is raised by the booster pump 6, it will be apparent that the physical characteristics of the water are so changed as to render it capable of absorbing additional carbon dioxide. This results in the production of an under-saturated solution within the storage reservoir 9. The pump is preferably operated in such manner as to increase the pressure on the water to a point corresponding substantially to bottling machine pressure, whereby the water in under-saturated condition may be expeditiously fed from the storage reservoir directly to the bottling machine without interpositioning of any regulating valves. This provides a convenient and inexpensive apparatus for effecting the desired low carbonation of water at the pressure required by the bottling machine.

As it is desirable, for the reasons pointed out herein, to supply the water to the bottling machine at a comparatively definite pressure, means is preferably provided for preventing the pump from producing too high a pressure. This may be accomplished, with the form of the invention illustrated in Figure 2, by providing between the con-

nections 5 and 8 a bypass connection 11. This bypass is normally closed by a valve 12 operated by a diaphragm 13. The diaphragm 13 is normally urged in a direction to close the valve by pressure supplied thereto in any desired manner, as by a tank 14. The pressure in the tank 14 may be varied to correspond to the desired bottling machine pressure and thereby maintain the bypass closed so long as the pressure at the outlet of the pump is less than or equal to the desired bottling pressure. If the pressure at the outlet of the pump exceeds the desired pressure, the water will be effective for moving the diaphragm 13 in the opposite direction to thereby open the valve 12. This will permit the water to continuously flow in a closed cycle from the outlet of the pump to the inlet, whereby no change in pressure within the storage reservoir 9 will be effected.

In Figure 3 of the drawings there is illustrated a slightly modified embodiment of the invention, in which parts corresponding to the parts already described are indicated by the same reference characters having a prime affixed thereto. In this form of the invention, the bypass is so arranged that when the bottling machine pressure is reached the load on the pump is decreased. This is accomplished by locating the bypass around the inlet side only of the pump, making it unnecessary for the water within the pump cylinder to pass through the outlet valve into a region of higher pressure. For maintaining the valve 12' properly balanced there may be provided a balancing connection 15, as will be well understood.

As the carbonator produces substantially uniform carbonation, and as the pressure at the outlet of the booster pump may be accurately controlled in the automatic manner referred to, it will be apparent that a uniformity of product is insured, as with a definite carbonation and uniform pressure and temperature such results must follow.

The present apparatus also lends itself admirably to the bottling of still goods requiring no carbonation. This result may be easily accomplished by cutting off the supply of carbon dioxide gas through the connection 3 and only supplying to the carbonator sweet water through the connection 4. The pressure in the tank 14 having been set to maintain the desired bottling machine pressure, it will be apparent that the operation of the booster pump 6 will be effective for withdrawing the sweet water from the carbonator at the pressure of the carbonator, irrespective of what this pressure may be, and raising the same to the bottling machine pressure as determined by the tank 14. As the carbonator at such times is not relied upon, it will be obvious that the sweet water may be directly supplied to the booster pump 130

from any other desired source, as for example the connection 16.

The advantages of the present invention arise from the provision of a carbonating apparatus and a method of carbonating for use in connection with bottling machines by means of which water having a uniform low carbonation may be produced.

We claim:

1. In the method of bottling, the steps consisting in carbonating water to substantially the saturation point, then raising the pressure on the water to render it capable of absorbing additional carbon dioxide gas, and thereafter maintaining it out of contact with additional carbon dioxide gas, substantially as described.

2. In the method of bottling, the steps consisting in carbonating water to substantially the saturation point at a pressure below the bottling machine pressure, then raising the pressure on the water to render it capable of absorbing additional carbon dioxide, and maintaining the water in such under-saturated condition until used, substantially as described.

3. In the method of bottling, the steps consisting in carbonating water to substantially the saturation point, then treating the water prior to bottling to change its pressure conditions and thereby its physical characteristics with respect to carbon dioxide absorption whereby it is under saturated at such pressure conditions, and then maintaining the water in such under-saturated condition until bottled, substantially as described.

4. In the method of bottling, the steps consisting in carbonating water to substantially the saturation point, passing said water to a bottling machine, increasing the

pressure on the water during its passage to the bottling machine, and thereafter maintaining it out of contact with additional carbon dioxide gas, substantially as described.

5. In the method of bottling, the steps consisting in carbonating water to substantially the saturation point, passing said water to a bottling machine, uniformly increasing the pressure on the water during its passage to the bottling machine, and thereafter maintaining the water in such under-saturated condition, until used, substantially as described.

6. In a carbonating apparatus, a storage reservoir, a carbonator for carbonating water to substantially the saturation point, a connection between the carbonator and the storage reservoir, means in said connection for raising the pressure of the water during its passage from the carbonator to the reservoir to produce in the reservoir an under-saturated solution, and connections arranged to deliver said under-saturated water as such to a bottling machine, substantially as described.

7. In a carbonating apparatus, a carbonator, pressure boosting means cooperating therewith, means governing the pressure established by said pressure boosting means, a connection between the carbonator and the pressure boosting means whereby carbonated water may be supplied to said boosting means, a source of sweet water, and means for supplying the same to said pressure boosting means, substantially as described.

In testimony whereof we have hereunto set our hands.

PATRICK W. SHIELDS.
LOUIS DE MARKUS.
